UNITED STATES PATENT OFFICE.

CHARLES L. LOW, OF FRESNO, CALIFORNIA, ASSIGNOR TO LISENBY MANUFACTURING COMPANY, OF FRESNO, CALIFORNIA, A CORPORATION.

FORM-ROLLER STRUCTURE FOR PRINTING PRESSES.

Application filed July 1, 1924. Serial No. 723,515.

To all whom it may concern:

Be it known that I, CHARLES L. Low, a citizen of the United States, residing at Fresno, county of Fresno, State of California, have invented certain new and useful Improvements in Form-Roller Structures for Printing Presses; and I do declare the following to be a full, clear, and exact description of the same, reference being had 10 to the accompanying drawings, and to the characters of reference marked thereon, which form a part of this application.

This invention relates to improvements 15 in the construction and arrangement of form-roller units used in printing presses of a certain character, to take the ink from the ink plates and distribute it over the type on the type-form.

The particular type of press on which my 20 structure is mounted is as shown in my co-pending application for patent, Serial No. 722,732, filed June 27th, 1924, and includes a reciprocating moving bed having a type-form and fixed ink plates beyond the form on both ends, the press being especially designed for two-color printing. The form roller units are disposed in fixed relation to the moving bed, there being one such unit 25 for each plate adapted to take ink from the latter and distribute it over a certain portion of the type on the form with the reciprocation of the moving bed.

One of the principal objects of my invention 30 is to arrange and mount each unit so that it is readily adjustable horizontally relative to the type form, so that the unit, with the reciprocation of the bed through a fixed distance will cover and ink different amounts of type on the form.

By this means, only a few lines of type on 35 the form from one end thereof may be inked with one color, or a greater number of lines may be so inked, depending on the setting 40 of the form roller unit relative to the limits of movement of the form.

The other form roller unit may be correspondingly and independently arranged, so as to ink the necessary amount of type 45 with another color from the opposite end of the form.

Another main object is to provide for a positive and even distribution of ink over 50 the surfaces of the form rollers regardless

of the even spread of ink on the ink plate, so that the type in turn will be evenly inked. 55

A further object of the invention is to produce a simple and inexpensive device and yet one which will be exceedingly effective for the purposes for which it is designed.

These objects I accomplish by means of 60 such structure and relative arrangement of parts as will fully appear by a perusal of the following specification and claims.

In the drawings similar characters of reference indicate corresponding parts in the 65 several views.

Fig. 1 is a fragmentary side outline of a press, partly broken out, showing my improved form roller units mounted thereon.

Fig. 2 is a top plan view of a roller unit. 70

Fig. 3 is an end view of the same.

Figs. 4 and 5 are cross sections both on the line 4—4 of Fig. 3, looking in opposite directions.

Referring now more particularly to the 75 characters of reference on the drawings, the press includes a frame or stand 1, having a reciprocating moving bed 2 slidably mounted therein. This bed is reciprocated through a fixed distance by means of a link 3 attached thereto and to a rocking lever 4 which is oscillated by a connecting rod 5 attached thereto and to the crank 6 of a driven shaft 7.

The bed has a centrally disposed type-form 8, adapted to cooperate with a printing cylinder 9 thereabove, and fixed ink plates 10 beyond the form at both ends thereof. 85

For each ink plate is a form roller unit, 90 each comprising transversely spaced blocks 11 and 12 disposed above the side rails 1^a of the frame. The block 11 is turnably and slidably mounted on a rigid rod 13 of a greater length than the block mounted on the adjacent side rail 1^a.

The other block 12 rests on the opposite side rail 1^a, and is adjustably clamped there-to by suitable clamping means 14 mounted on the block and engaging the under side 100 of the overhanging flange of said side rail.

Journalized in and extending between said blocks is a shaft 15 having a pinion 16 meshing with a rack 17 fixed in connection with the moving bed and extending lengthwise thereof adjacent one side rail. This pinion 105

meshes with a gear 18 of greater width than the pinion fixed on a shaft 19 slidably journaled in the blocks above the shaft 15. A roller 20 is fixed on the shaft 19 between 5 the gear and the opposite block.

On one end of the shaft 19, outwardly of the block 11, is a circumferentially grooved disc 21 in the groove of which projects a roller 22 mounted on the upper end 10 of an arm 23 adjustably fixed at its lower end on a horizontal shaft 24 journaled on the frame 1 outside the same.

This shaft is oscillated through a certain arc, so as to impart a transverse reciprocatory movement to the upper end of the arm 23, by means of a rod 25 having an eccentric connection with the drive shaft 7 and projecting upwardly thence to a connection with a crank 26 on the shaft 24. By 20 reason of this construction, it will be seen that with the rotation of the shaft 7, the shaft 24 is constantly oscillated, imparting a constant reciprocation to the arm 23 and consequently a similar movement to the shaft 19 and roller 20. The width of the gear 18 relative to the longitudinal movement of the shaft 19 is such that the gear is always maintained in mesh with the pinion 16.

30 Bearing blocks 27 are pivotally mounted on the blocks 11 and 12, on pins 27^a in spaced relation longitudinally of the press for rocking movement in a longitudinal vertical plane. These bearing blocks partly overhang the main blocks 11 and 12 on which they are mounted, and are clamped against rocking movement in any desired position by means of adjustment screws 28 mounted in the overhanging portions of said blocks 27 40 on both sides of their swivel connections and bearing against the upper faces of the main blocks 11 and 12.

45 Shafts 29 are removably journaled in the blocks 27 and carry the ink rolls 30 of the usual soft composition, the roller 20 being of steel or the like. The rolls are arranged to engage both the roller 20 and the ink plates, as well of course as the type on the form 8.

50 The individual adjustability of the blocks 27 in which said rolls are mounted enables the degree of contact of the rolls with the above named elements to be regulated as may be necessary.

55 By reason of the constant rubbing action of the roller 20 along the rolls 30, in addition to its rotary movement, it will be clear that any ink on said rolls will be evenly distributed over the surface thereof.

60 Since the type form can only advance to a certain point in the length of the press frame on which the roller units are fixed, it will be evident that if the latter are shifted along the frame in one direction or the other, the extent of length of the type form

which they will overhang or cover with the reciprocation of the bed will differ with different settings of the roller units. When the units are thus adjusted the arms 23 are of course shifted also to maintain their 70 proper positions relative to said units.

If the clamp means 14 is disengaged from the side rail of the frame, the roller unit may be swung up about the rod 13 as an axis without disconnecting or removing any 75 part, thus enabling the ink plate to be cleaned without interference.

From the foregoing description it will be readily seen that I have produced such a device as substantially fulfills the objects 80 of the invention as set forth herein.

While this specification sets forth in detail the present and preferred construction of the device, still in practice such deviations from such detail may be resorted to as do not form a departure from the spirit of the invention as defined by the appended claims.

Having thus described my invention what I claim as new and useful and desire to secure by Letters Patent is:

1. In a printing press having a frame, and a type-form mounted therein for reciprocation through a fixed distance, a form roller unit mounted on the frame above the plane of the form for longitudinal sliding adjustment, said unit including supporting blocks above the side rails of the frame, a longitudinally disposed rod supported from the frame and on which one of the blocks is both slidably and turnably mounted, and clamping means disengageable at will between the other block and the adjacent frame member, whereby to allow the unit to be swung upwardly about the rod as an axis.

2. In a printing press having spaced frames, a form roller unit extending transversely thereof, and a member fixed on one frame and on which the adjacent end of the unit is both pivoted and longitudinally adjustable, the other end of said unit resting on the opposite frame, and means mounted on said last named end of the unit for enabling the same to be detachably clamped onto the frame.

3. In a printing press having spaced frames, a form roller unit mounted on the frames and extending transversely thereof, said unit including end members, and a single supporting means between one frame and one of said end members for enabling the unit to be both moved longitudinally of the frame and swung upwardly about said means as an axis, the other end member resting on the opposite frame.

4. A form roller structure comprising main supporting members, a roller journaled therein and extending therebetween, blocks pivoted onto said members to one side of the roller and arranged for limited swing-

ing movement in planes at right angles to the axis of the roller, adjustment screws threaded through the blocks to the sides of their pivots, and bearing against the supporting members, and an ink roll supported by the blocks.

5. In a printing press having a frame a form roller unit mounted thereon for longitudinal adjustment, said unit including

a roll, a shaft extending longitudinally of the frame, means for oscillating said shaft with the operation of the press, a grooved member mounted in axial connection with the roll, and an arm engaging said member and adjustably clamped on the shaft for 15 longitudinal adjustment thereon.

In testimony whereof I affix my signature.

CHARLES L. LOW.
